UNITED STATES PATENT OFFICE.

HERBERT EDWARD WALKER, OF CHICAGO, ILLINOIS.

STORAGE-BATTERY CLIP.

Application filed July 21, 1923. Serial No. 578,552.

To all whom it may concern:

Be it known that I, HERBERT E. WALKER, a citizen of the United States, and a resident of Chicago, in the county of Cook and State of Illinois, have invented certain new and useful Improvements in Storage-Battery Clips; and I do hereby declare that the following is a full, clear, and exact description thereof, reference being had to the accompanying drawings, and to the characters of reference marked thereon, which form a part of this specification.

This invention relates to improvements in storage battery clips of that general type shown in my United States Letters Patent, No. 1,439,457, granted December 19, 1922, and other clips designed for generally similar purposes.

The object of the present invention is to simplify the manufacture and assembly of the elements of the clip, to reduce the cost of assembling the clip and to reduce the amount and cost of metal required to form the clip.

As shown in my aforesaid application, the jaw members of the clip are made plain, at their ends to engage over and be attached to a spacing and attaching member, there being a terminal member integral with a part of the spacing and connecting member, said jaw members having substantially straight shanks arranged at an acute angle to each other forwardly beyond the spacing and connecting member.

In the present invention the spacing and connecting member, as a separate part, is omitted and the shanks of the jaw members themselves are formed, one to constitute the spacing and attaching member, and the other being adapted to receive, or having integrally formed thereon, a terminal member or lug so that thereby, aside from the attaching rivet by which the parts are secured together, the clip can be made of two pieces.

In the drawings is shown a preferred embodiment of the invention, wherein:

Figure 1 is a perspective view of a clip embodying the invention.

Figure 2 is an enlarged longitudinal section of the terminal end of the clip.

Figure 3 is a rear face view of the part

of the clip which bears the terminal lug or member.

As shown in the drawings, 10, 10 designate the jaw members which are formed at their forward ends to provide jaws 11, 11 for grasping the element of a storage battery, or a like part, to which the clip is attached. The free ends of the jaws are inwardly turned and serrated in the usual manner to afford better grasping action of the jaws on the part to which the clip is attached. The jaws 11 are made of the same width as the members 10, and said jaw members are cut away in rear of the jaws to produce crossed connecting members 12, 12 which are stiffened by forming thereon longitudinal ribs or beads. The construction of the forward end of the clip may be varied within the spirit and scope of the invention.

One of the jaw members is turned back on the body of the member at an oblique angle thereto to form a seat member 13, disposed at an acute angle to its companion jaw member, and said seat member terminates in an out-turned terminal 14, the end edge of which bears against the inner face of the jaw member 10 from which the seat member 13 is formed. This construction produces, at the rear end of one of the jaw members, a wedge-shaped formation whose wider end is directed forwardly towards the jaws 11. The other jaw member 10 is made slightly longer than its companion jaw member and lies on the outer face of the seat member 13. The plain rear end of the longer jaw member and corresponding bearing part of the seat member 13, and the other jaw member 10 are formed with aligned openings to receive a rivet 15 or other attaching means by which one of the jaw members is fixedly attached to the other jaw member. As herein shown the said rivet openings are located near the apex of the wedge-shaped formation of the jaw carrying the members 13 and 14.

The longer jaw member 10 is provided with an integral rearward extension 16 which is formed to produce a terminal lug or member to which is adapted to be connected the conductor 17 leading from a source of current supply. The said lug 16 is shown as provided with out-turned marginal lips 18, 18 to produce a channel or

trough-like member to receive and to grasp the conductor 17. The conductor may be attached to said lug by any suitable means to afford a good electrical connection between the conductor and lug, and also preferably by means which affords a good mechanical connection between said parts.

As herein shown, the lug is provided at its narrow neck portion 19 with an aperture 20 made of a size to snugly receive the conductor 17. The clip end of the conductor is bared of its insulation and said bared conductor is laced in the trough-like terminal and is threaded through the aperture 20 and turned backwardly on the rear side of the lug and attached thereto in any suitable manner. Such attachment may be effected by soldering, but by preference a positive attachment is made between the free end of the bared conductor and a hook 21 which is struck out of and turned backwardly from the metal of the terminal lug. Said free end of the conductor 17 is laid under said hook after which the free end of the hook is bent inwardly over the conductor to clasp the same. The means herein shown for connecting the conductor to the terminal lug provides a good area of electrical contact between the bared conductor and lug, and additionally provides a strong connection between said conductor and the clip. This latter phase of the connection is desirable inasmuch as it prevents the conductor being stripped from the clip when the clip is pulled off the battery element, or other part to which the clip is applied, by force exerted on the conductor, such as may occur in a careless operation of detaching the conductor from the battery element.

From what has been said, it will be seen that the clip shown is exceedingly simple in its construction and the mode of its assembly, and that the back-turned end of one of the jaw members provides efficient fulcrums about which the jaw members are flexed when said jaw members are pressed together to separate the jaws.

It is to be understood that the invention is not intended to be limited to the precise con-

struction shown and described, except as to claims wherein the particular details of the construction are specifically set forth.

I claim:

1. A clip comprising two opposed separate resilient jaw members disposed at an acute angle to each other, one of the jaw members being formed to provide an integral seat for the other jaw member to predetermine said angle and means for attaching the jaw members together. 60

2. A clip comprising two opposed separate resilient jaw members disposed at an acute angle to each other, one of the jaw members being formed to provide an integral seat for the other jaw member to predetermine said angle, the other jaw member being formed with an integral terminal lug, and means at said seat for attaching the jaw members together. 65

3. A clip for the purpose set forth comprising two jaw members disposed at an acute angle to each other, one of the jaw members being turned backwardly on itself to provide a seat for the other jaw member, said seat being disposed at an acute angle to the jaw from which it is formed, and means piercing said jaw members at said seat to fasten them rigidly together. 70 75

4. A clip for the purpose set forth comprising two jaw members disposed and secured together at an acute angle to each other, one of the jaw members being turned backwardly on itself to provide an oblique seat for the other jaw member, and provided with a terminal adapted to abut against the latter jaw member. 80 85

5. A clip made of two separate spring jaw members integral in themselves and having jaws and relatively disposed to spring-hold the jaws closed, and including also spacing means integral with and inclined to one member to which the other member is fixedly attached. 90

In witness whereof I claim the foregoing as my invention, I hereunto append my signature this 24th day of July, 1922. 95

HERBERT EDWARD WALKER.

trough-like member to receive and to grasp the conductor 17. The conductor may be attached to said lug by any suitable means to afford a good electrical connection between the conductor and lug, and also preferably by means which affords a good mechanical connection between said parts.

As herein shown, the lug is provided at its narrow neck portion 19 with an aperture 20 made of a size to snugly receive the conductor 17. The clip end of the conductor is bared of its insulation and said bared conductor is laced in the trough-like terminal and is threaded through the aperture 20 and turned backwardly on the rear side of the lug and attached thereto in any suitable manner. Such attachment may be effected by soldering, but by preference a positive attachment is made between the free end of the bared conductor and a hook 21 which is struck out of and turned backwardly from the metal of the terminal lug. Said free end of the conductor 17 is laid under said hook after which the free end of the hook is bent inwardly over the conductor to clasp the same. The means herein shown for connecting the conductor to the terminal lug provides a good area of electrical contact between the bared conductor and lug, and additionally provides a strong connection between said conductor and the clip. This latter phase of the connection is desirable inasmuch as it prevents the conductor being stripped from the clip when the clip is pulled off the battery element, or other part to which the clip is applied, by force exerted on the conductor, such as may occur in a careless operation of detaching the conductor from the battery element.

From what has been said, it will be seen that the clip shown is exceedingly simple in its construction and the mode of its assembly, and that the back-turned end of one of the jaw members provides efficient fulcrums about which the jaw members are flexed when said jaw members are pressed together to separate the jaws.

It is to be understood that the invention is not intended to be limited to the precise con-

struction shown and described, except as to claims wherein the particular details of the construction are specifically set forth.

I claim:

1. A clip comprising two opposed separate resilient jaw members disposed at an acute angle to each other, one of the jaw members being formed to provide an integral seat for the other jaw member to predetermine said angle and means for attaching the jaw members together.

2. A clip comprising two opposed separate resilient jaw members disposed at an acute angle to each other, one of the jaw members being formed to provide an integral seat for the other jaw member to predetermine said angle, the other jaw member being formed with an integral terminal lug, and means at said seat for attaching the jaw members together.

3. A clip for the purpose set forth comprising two jaw members disposed at an acute angle to each other, one of the jaw members being turned backwardly on itself to provide a seat for the other jaw member, said seat being disposed at an acute angle to the jaw from which it is formed, and means piercing said jaw members at said seat to fasten them rigidly together.

4. A clip for the purpose set forth comprising two jaw members disposed and secured together at an acute angle to each other, one of the jaw members being turned backwardly on itself to provide an oblique seat for the other jaw member, and provided with a terminal adapted to abut against the latter jaw member.

5. A clip made of two separate spring jaw members integral in themselves and having jaws and relatively disposed to spring-hold the jaws closed, and including also spacing means integral with and inclined to one member to which the other member is fixedly attached.

In witness whereof I claim the foregoing as my invention, I hereunto append my signature this 24th day of July, 1922.

HERBERT EDWARD WALKER.

Certificate of Correction.

It is hereby certified that Letters Patent No. 1,558,431, granted October 20, 1925, upon the application of Herbert Edward Walker, of Chicago, Illinois, for an improvement in "Storage-Battery Clips," were erroneously issued to the inventor, said Walker, whereas said Letters Patent should have been issued to *Edgar M. Shanklin, George R. Shanklin, and W. E. Shanklin, partners as Shanklin Manufacturing Company, of Springfield, Illinois*, as assignees of the entire interest in said invention, as shown by the records of assignments in this office; and that the said Letters Patent should be read with this correction therein that the same may conform to the record of the case in the Patent Office.

Signed and sealed this 17th day of November, A. D. 1925.
